UNITED STATES PATENT OFFICE

SAMUEL KELLETT, OF SAN FRANCISCO, CALIFORNIA.

DESIGN FOR CENTER-PIECE IN ALTO-RELIEVO.

Specification forming part of Design No. 5,999, dated July 16, 1872.

SPECIFICATION.

To all whom it may concern:

Be it known that I, SAMUEL KELLETT, of San Francisco, in the county of San Francisco and State of California, have invented and produced a new and original Design for Center-Piece in Alto-Relievo; and I do hereby declare that the following is a full and exact description of the same, reference being had to the accompanying drawing and to the letters of reference marked thereon.

My new design consists of a rosette, A, from beneath which radiate arms B, and between which are figures of shell-work C. The whole is mounted upon or forms a disk, having a molded ring D, surrounded by shell-work E,

with vines F between, and scalloped raised edge. Around this is a ring or edge, consisting of scroll-work G and architectural figures H.

Having thus described my invention, what I claim, and desire to secure by Letters Patent, is—

The radial arms B, shell-work C E, vine-work F, scroll-work G H, separate or in combination, set forth and shown.

In witness whereof I hereunto set my hand and seal.

SAML. KELLETT. [L. S.]

Witnesses:

C. W. M. SMITH,
E. V. SUTTER.
